UNITED STATES PATENT OFFICE.

FRANK SPENCER LEWIS, OF PHILADELPHIA, PENNSYLVANIA.

METHOD OF AND APPARATUS FOR CENTRIFUGAL CONCENTRATION.

Application filed January 31, 1923, Serial No. 615,993. Renewed April 12, 1926.

My invention relates to separating and concentrating the various metallic or other substances from each other or from the waste material generally known as the 5 gangue.

The method now employed, after the material has been ground fine enough to release the values from the waste, requires it to be screened to different sizes which are there- 10 after separately concentrated in various ways. The capacity of the various means now employed decreases rapidly as the size of the ground particles decreases.

One object of the present invention is to 15 overcome these defects and disadvantages and to make a concentration of all the sizes at once and, generally stated, this is done, according to this invention, by subjecting the material bearing fluid to centrifugal and 20 centripetal forces in positive relation at one and the same time or, more accurately, by subjecting the material to the resultant of centrifugal force and of a force acting centripetally.

25 This result may be accomplished by the new and novel method through the agency of a cylinder fitted with inlet and outlet pipes at opposite ends and arranged for revolution in a tank containing liquid and having slots or perforations provided through the outer shell and equipped with cups or lips on the outside. The material to be treated mixed with a fluid is forced by a pump or other means through the cylinder which 30 is made to revolve in the tank of fluid at a speed appropriate to drive out through the slots or perforations the particles of relatively heavy specific gravity by centrifugal force while the water and the gangue are 35 prevented from being forced out by the centripetal force of the inflow of the fluid from the outer tank in which such cylinder revolves, the cup or lip formation on the outside of the cylinder causing a scooping action 40 which drives the fluid from the tank into the cylinder from which it is carried with the fluid and gangue therein through the discharge pipe from the concentrator, any change in the speed of revolution of the 45 cylinder having no effect on the relations of the said centrifugal and centripetal pressure to each other or on the resultant of those forces.

50 The invention also comprises the improvements to be presently described and finally claimed.

In the following description reference will be made to the accompanying drawings forming part hereof.

Figure 1 is an elevation, partly in section, 50 showing apparatus embodying features of the invention, and

Fig. 2 is a cross-section on the line 2—2 of Figure 1 drawn to an enlarged scale.

Referring to the drawings, 1 is a hollow cylinder provided with a hollow shaft extension 2 through which the material is received and with a hollow extension 3 through which the material is discharged after treatment. These hollow shafts are supported on 70 the bearings 4, which may be of the ball, roller or other type, and through packing glands 5 they turn, without leakage of material, in respect to the fixed inlet and outlet connections *a* and *b*, and the whole is made 75 to revolve by pulley 6. 7 is an open tank to contain fluid surrounding the cylinder 1. 8 are washers to prevent leakage of fluid from tank 7. Within the cylinder 1 there is a second cylinder or drum 9 suitably held in position to keep the outside of said cylinder 9 spaced equi-distant from the inside of the outer cylinder 1. Running lengthwise of the outer cylinder are slots 10 into which are introduced strips 11 running lengthwise in the slots and suitably held in position and projecting beyond the outer surface of the cylinder 1 and of such shape as to cause the fluid in the tank 7 to be drawn inwardly into cylinder 1 when the latter is in rotation. 80 The strips 11 may be made to project from the surface of the cylinder 1 to a decreasing extent from the feed end toward the discharge end of the cylinder to progressively reduce the pressure of the inward flow from 85 the tank to the revolving cylinder so that the heavier concentrates only will be thrown out of the cylinder 1 as the material first reaches the slots or perforations 10, and the less heavy concentrates due to decreased pressure, will be discharged along the line of 90 such slots or perforations, so that the various concentrates will fall in various subdivisions at the bottom of the tank from which they can be withdrawn. 100

Obviously modifications may be made in details of construction, procedure and operation, without departing from the spirit of the invention, which is not limited as to such matters or otherwise than as the prior 110 art and the appended claims may require.

I claim:

2

1. The method of concentration which consists in establishing a flowing stream mixed with the material to be treated and a second body of fluid by interposing between them a perforated rotating cylindrical wall having centripetally acting impellers, and selectively passing material from the stream through the perforations to the body by subjecting the material to the resultant of centrifugally and centripetally acting forces consequent upon the rotation of the impellers and wall, substantially as described.

2. The method of concentration which consists in establishing a flowing stream mixed with the material to be treated and a second body of fluid by interposing between them a perforated rotating cylindrical wall having centripetally acting impellers, and selectively passing material from the stream outwardly through the perforations in opposition to flow of fluid inwards through the perforations by subjecting the material to the resultant of centrifugal force and inward flow consequent upon the rotation of the wall and the scooping action of the impellers.

3. Apparatus for concentration which comprises a rotating cylinder internally and externally supplied with fluid and provided at its curved wall with perforations and complementary impellers, whereby the resultant of the outward centrifugal force due to rotation and the inward force due to the scooping action of the impellers is available for selectively passing material from the interior of the cylinder through the perforations to the exterior of the cylinder in opposition to the inward flow of fluid.

4. Apparatus for concentration having in combination a rotary perforated cylinder through which fluid and material are introduced and which is submerged in fluid and provided with impellers for establishing inward flow against selective centrifugal expulsion of material, substantially as described.

5. Centrifugal concentration apparatus which consists of a cylinder through which the material bearing fluid is forced and

which has slots or perforations in its outer surface to bring about a centrifugal pressure in proportion to its rate of revolution, a tank containing fluid in which said cylinder is immersed, said slots or perforations being provided with outward projections to bring about by the same revolution of the cylinder a centripetal pressure of inflowing fluid of sufficient intensity to allow only that portion of the material which is of a greater specific gravity than the gangue to be driven from the cylinder in opposition to such inflowing fluid, the centrifugal and centripetal pressures being in positive relation at one and at the same time irrespective of the speed of revolution of the cylinder.

6. Centrifugal concentrating apparatus comprising the combination of a revolvable cylinder provided with a drum or cylinder of such smaller dimensions that when same is centrally secured within the outer cylinder there will be sufficient space between the cylinders to allow the flow of material bearing fluid to pass through the machine, means for rotating such cylinder, a tank also containing fluid in which the cylinder is rotated, said outer cylinder being equipped with slots or perforations disposed at a suitable angle to permit the outward flow of concentrates, said slots or perforations having projecting strips curved or shaped to cause a scooping or centripetal action resulting in an inflowing current of fluid from the tank into the revolving cylinder of sufficient intensity to prevent the feed fluid and the lighter material or gangue from passing by centrifugal pressure from the revolving cylinder into the tank.

7. Centrifugal concentrating apparatus as described in claim 6 in which the projecting strips contiguous to the slots or perforations are of decreasing size from the feed end of the cylinder towards the discharge end of the cylinder in order to reduce the centripetal pressure of the inflow from the tank into the revolving cylinder, and thereby permit the concentrates of lesser specific gravity also to be driven out of cylinder into the tank.

FRANK SPENCER LEWIS.
